UNITED STATES PATENT OFFICE

2,382,217

CONCENTRIC TRANSMISSION LINE
TERMINATION

Henry B. Fancher, Scotia, N. Y., assignor to General Electric Company, a corporation of New York

Application March 16, 1943, Serial No. 479,347

4 Claims. (Cl. 178—44)

My invention relates to concentric transmission lines, and it has for an object to provide an improved and simplified means for terminating such lines and connecting them with exterior circuits.

It is frequently desirable to provide, at the end of a concentric transmission line having an inner conductor and a tubular outer conductor concentric therewith, means for supporting the inner and outer conductors in fixed relation. It is also desirable in many cases that such means should act to seal the outer conductor against the passage of gas or water to prevent moisture from entering the transmission line, or to allow the line to be filled with gas under pressure. It is accordingly an object of my invention to provide such supporting means at the end of a transmission line having an improved and simplified form and in which the lump capacity presented across the end of the line by the supporting means is caused to have substantially negligible effect on the line and its connected circuits.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 represents one embodiment of my invention and Fig. 2 is a modification thereof.

In Fig. 1 a carrier wave source 10 supplies carrier waves through a concentric transmission line 11 to an antenna 12 from which such waves are radiated. Oscillations from the source 10 are impressed across the terminals of an output circuit 13, of which one terminal is grounded. The major portion of the outer conductor 14 of the transmission line 11 is grounded at various points along its length, and one end 15 of the inner conductor 16 is connected to a point on the tuned circuit 13 between the terminals thereof. At the other end of the transmission line, a continuation of the inner conductor 16 forms the antenna 12.

In order to present minimum lump capacitance across the end of the line 11, as well as to seal the line hermetically against the passage of gas or liquid, each end of the transmission line 11 is terminated by a termination structure 17. The structure 17 comprises a tubular conductor 18 having a diameter somewhat larger than that of the outer conductor 14 of transmission line 11 and a length equal to the length of a quarter wave at the operating frequency of the source 10.

Conductor 18 is mounted concentrically with the inner and outer conductors 16 and 14 of the line 11 and is so located that one end of the conductor 18 is adjacent the end of the conductor 14. The other end of conductor 18 is rigidly fastened to the outer conductor 14 by a conductive connection 19 having considerable strength and which may be formed of any suitable conducting material, such as metal. Conductor 18 is not grounded throughout its length except through the member 19 which is conductively attached to the grounded outer conductor 14. A cup-shaped insulating disk 20 is secured to the free end of conductor 18 and supports the end 15 of inner conductor 16 in rigid relation with respect to outer conductor 14 of line 11. Disk 20 may be formed of any suitable insulating material, for example, a ceramic-bonded mica insulating material, such as Mycalex, and may be united to conductors 15 and 18 in any well known manner.

Conductor 18, member 19 which supports it on the outer conductor 14, and insulator 20 are structurally rigid enough to resist both lateral and longitudinal motions of the inner conductor 16 with respect to the outer conductor 14. Furthermore, these parts form a closure over the end of the outer conductor 14, so that the transmission line 11 is hermetically sealed. By such sealing the entrance of moisture by condensation, or the like, is prevented, and the characteristics of the line are maintained unchanged. If it is desired to fill the transmission line 11 with an inert gas under high pressure, the seal formed by the elements 18, 19 and 20 of the structure 17 is of a type capable of withstanding such gas pressure and preventing leakage of the gas.

When an insulator is connected directly between the inner conductor 16 and the end of the outer conductor 14, it presents a lumped capacitance at the end of the transmission line 11, which, in conjunction with other portions of the transmission line and the interconnected circuit, makes the entire system have a narrow band pass characteristic. This is due to the discontinuity introduced by the lumped capacitance which can usually be compensated only over a relatively narrow band. Such a condition is highly undesirable in certain application such as, for example, in the transmission of television signals requiring very broad band pass characteristics. By the provision of the structure 17 substantially no effective capacitance is added between the outer conductor 14 and the inner conductor 16. This is brought about by the fact that the capacitance through insulator 20 is effectively in series with the con-

ductor 18, which, with the outer conductor 14, forms a short section of concentric transmission line having a length equal to a quarter wave length at the operating frequency of waves from the source 10. This short section of line is short-circuited at one end by member 19 so that the impedance at its opposite end, by well known transmission line theory, is of extremely high value. The structure 17 therefore presents between the outer conductor 14 and the inner conductor 16 an extremely high impedance in series with the capacitance of the insulator 20, the effect of the capacitance of this combination on the line 11 being rendered substantially negligible by the series resistance.

It should be noted that, in television applications where extremely wide band widths are utilized for signaling, the length of the conductor 18, while having a length equal to a quarter wave length at carrier frequency, may be somewhat different from a quarter wave in length at side band frequencies widely removed from the carrier frequency. However, for band widths normally used in television practice, the impedance of the short section of line formed by conductors 18 and 16 is very much higher than the reactance of the insulator 20 even at side band frequencies widely removed from the frequency of waves from the source 10. The effect of the capacitance of the insulator 20 therefore remains negligible at all frequencies to be transmitted, even when such frequencies are considerably different from that frequency at which the conductor 18 is exactly a quarter wave length. The effect of the reduced impedance of the above mentioned short section of transmission line at frequencies widely spaced from the carrier frequency may be minimized by choosing a frequency in the middle of the band to be transmitted, and making conductor 18 of such length that this section of transmission line has a length exactly equal to a quarter wave length at this chosen frequency. This is especially important in television applications where single sideband transmission is normally used; in such applications, the chosen frequency will be different from the nominal carrier frequency.

At the end of transmission line 11 adjacent antenna 12 a structure 21, similar to the structure 17, is utilized to maintain the inner conductor 16 in fixed relation with outer conductor 14 at that end of the line 11. As shown in the drawing, the end of the line 11 adjacent the antenna 12 is vertically disposed and, in some cases, may extend a considerable distance above the earth. In such cases outer conductor 14 may be additionally supported, as from a tower, and the structure 21 may be utilized as means to support the inner conductor 16 in a fixed position within the outer conductor 14.

In the equipment illustrated in Fig. 2 a carrier wave source 30 having a balanced, or push-pull, output circuit 31, grounded at a central point 32 transmits waves through a pair of transmission lines 33 and 34 respectively to the two halves of a dipole antenna 35 and 36. The inner conductor 37 of the transmission line 34 is connected to the tuned output circuit 31 at one side of the ground point 32, while the inner conductor 38 of the transmission line 33 is connected to the output circuit 31 at the other side of the ground point 32. The other end of the inner conductor 37 is extended to form the element 35 of the dipole antenna, and the inner conductor 38 is extended similarly in the opposite direction to form the other element 36 of the antenna.

The outer conductors of the lines 33 and 34 are grounded throughout the major portion of their length, and each line is terminated at each end by a structure 40, which is similar to the structure 17 of Fig. 1.

In a push-pull circuit of the type shown in Fig. 2, it is particularly desirable that the surge impedance of the connecting lines 33 and 34 be maintained constant and that discontinuities which cause undesirable reflections be avoided. Such a result is obtained by use of my improved termination means 40 which isolate the lump capacitances of the insulators 20 from the lines 33 and 34 by inserting suitable short sections of a transmission line to present a high impedance between the ends of lines 33 and 34 and the insulators 20.

While I have shown particular embodiments of my invention, it will of course be understood that I do not wish to be limited thereto since various modifications may be made, and I contemplate by the appended claims to cover any such modifications as fall within the true spirit and scope of my invention.

What I claim as new and desire to secure by Letters Patent of the United States, is:

1. In a concentric transmission line for high frequency oscillations having inner and outer conductors, means for supporting said conductors in spaced relation at an end of said line comprising, a substantially inflexible tubular conductive sheath surrounding said outer conductor and having its end remote from the end of said line rigidly attached and conductively connected to said outer conductor, said sheath throughout its length having an inner diameter substantially larger than the outer diameter of said outer conductor and forming with said outer conductor a section of concentric transmission line short-circuited at one of its ends by said conductive connection, and solid dielectric means supporting said inner conductor in coaxial relationship with said sheath at its other end.

2. Termination means for the end of a concentric transmission line having coaxially spaced inner and outer conductors comprising, a tubular metal sheath encircling said outer conductor at said end and extending along said outer conductor for a distance substantially equal to a quarter wave length at the operating frequency of said line, the end of said sheath remote from said end of said line being conductively connected to said outer conductor, and insulating means supporting said inner conductor in coaxial relationship with said sheath at its other end.

3. In combination, a concentric transmission line for high frequency oscillations having an inner conductor and a tubular outer conductor, and means for sealing an end of said line and for reducing reflection of oscillations at said end, said means comprising, a tubular conductive sheath surrounding said inner conductor at said end and having a length equal to a quarter wave length at the frequency of said oscillations, the end of said sheath remote from said end of said line being conductively connected to said outer conductor to form therewith a section of a transmission line having a length equal to a quarter wave length at said frequency, and insulating means sealingly engaging both said inner conductor and the other end of said sheath and presenting an undesirable reactance therebetween, said section of transmission line presenting a high impedance in series with said reactance between said inner and outer conductors.

4. In combination, a gas-filled concentric transmission line for high frequency oscillations having an inner conductor and a tubular outer conductor, and means for sealing an end of said line and for reducing reflection of oscillations at said end, said means comprising, a tubular conductive sheath surrounding said inner conductor at said end and having a length equal to a quarter wave length at the frequency of said oscillations, the end of said sheath remote from said end of said line being conductively connected to said outer

10

conductor to form therewith a section of a transmission line having a length equal to a quarter wave length at said frequency, and insulating means sealingly engaging both said inner conductor and the other end of said sheath and presenting an undesirable reactance therebetween, said section of transmission line presenting a high impedance in series with said reactance between said inner and outer conductors.

HENRY B. FANCHER.
